UNITED STATES PATENT OFFICE.

OTTO PETERMANN, OF GROTON, NEW YORK, ASSIGNOR TO CORONA TYPEWRITER COMPANY, INC., A CORPORATION OF NEW YORK.

TYPE-WRITING MACHINE.

1,261,850.

Specification of Letters Patent.

Patented Apr. 9, 1918.

Application filed August 18, 1914. Serial No. 857,343.

To all whom it may concern:

Be it known that I, OTTO PETERMANN, a citizen of the Republic of Switzerland, and a resident of Groton, county of Tompkins, and State of New York, have invented certain new and useful Improvements in Type-Writing Machines, of which the following is a full, clear, and exact description.

10 This invention relates more particularly to the key action of front-strike or other visible typewriting machines.

One of the principal objects of the invention is to provide a key action which has 15 a very easy, velvety and uniform touch and in which the type-bars have an upward and rearward accelerated movement, and in such a way that a direct pull is effected between the key-levers or key-operated levers and the said type-bars.

Other objects of the invention are to provide a simple and efficient key action in which substantially all the parts may be punched from sheet steel or other suitable 25 material; to provide means whereby the parts of the key action may be readily made and assembled; and to provide a key action in which the construction is such that a minimum amount of frictional and wearing 30 surfaces are provided.

Another object of the invention is to provide simple and efficient means whereby all of the key-levers may be mounted upon a single rod or shaft and the key-levers and 35 parts operated thereby so constructed and arranged that substantially a uniform touch is obtained.

A further object of the invention is to provide a key action in which the type-bar 40 is connected to an auxiliary lever and the auxiliary levers connected by a floating and rocking link to a key-lever in such a way that the relation of the link and levers is changed to give an accelerated movement to 45 the type-bar.

A still further object of the invention is to provide a key action for various kinds of typewriters in which a minimum space with the least possible amount of material 50 is employed and which is particularly adapted for small portable machines.

With these and other objects in view, the invention will be hereinafter more particu-

larly described with reference to the accompanying drawings, which form a part 55 of this specification, and will then be pointed out in the claims at the end of the description.

In the drawings, Figure 1 is a vertical section, partly in elevation, and partly dia- 60 grammatic, of one form of machine embodying my invention.

Fig. 2 is a fragmentary transverse section of the machine showing several of the intermediate or auxiliary levers of the key 65 action.

Fig. 3 is a sectional plan, and Fig. 4 a perspective view of a slightly different form of floating link or connection between the key-levers and the auxiliary levers. 70

Fig. 5 is a side elevation, partly diagrammatic, of a key action somewhat different from that shown in Fig. 1, but embodying the same principle; and

Fig. 6 is a view similar to Fig. 5 except 75 that the parts are somewhat differently arranged.

The frame 10 may be of any suitable construction and above the frame may be arranged a platen 11. The platen may be 80 mounted upon a suitable carriage and this carriage may be controlled by the usual or any preferred form of escapement and 85 transmission or power means.

The escapement may be substantially the same as that shown in 85 the Reissue Patent No. 13,935, dated June 22, 1915, or may be of any other suitable construction. The escapement is adapted to be operated by a rocking frame, not shown, which may be moved by means of a 90 rod 12. This rod connects the arms of bell-crank levers 13 which are pivotally mounted at the upper rear portion of the frame and at each side thereof. One arm, as 14, of each bell-crank is provided with 95 a substantially triangular slot 15 in which the bent or inturned end 16 of an angularly arranged and reciprocating rod 17 is located. There is a rod 17 at each side of the machine and these rods are connected 100 by a transversely extending universal bar 18. The universal bar 18 has forked or bifurcated parts 19 which are adapted to span and be guided on a transversely extending shift rod 20, the latter serving as 105 the pivot or supporting means for the usual

shift levers, the latter forming no part of the present invention.

A series of levers 21 are pivotally mounted upon a rod or shaft 22 which extends transversely of the machine and is supported in the side members of the frame. Each key-lever is provided with a key or finger part 23 at one end and with an inwardly and downwardly extending arm 24. This arm 24 has an upturned end 24^a which may be bendable edgewise and is adapted to engage the under inclined surface of the universal bar 18 at the proper time so as to force the same upward to move the bell-crank levers on their pivot and thus operate the universal bar frame together with the escapement mechanism, the ribbon vibratory mechanism, and such other mechanism as may be employed, and such as may be operated through the universal bar during the depression of the keys. The key-levers are arranged in banks and being mounted on a single rod, the power arms thereof are therefore of different lengths. The inner arms 24 of the key-levers are also of relatively different lengths to compensate for the different lengths of the power arms of the key-levers so that the pressure necessary to operate the universal bar and different mechanisms by the different sets or banks of keys, will be substantially uniform.

The key-levers 21 each have an integral downwardly extending part or arm 25 located directly under the pivot rod 22. This arm 25 is provided with an elongated substantially vertical slot 26. A link 27 has an inturned or angular end 28 which is adapted to enter the slot 26 and has an inturned or angular end 29 which is adapted to enter the slot 30 in the lower arm of an auxiliary lever 31. There is a lever 31 for each key-lever and each auxiliary lever is pivoted on a transverse shaft or rod 31^a and has its upper end or arm 32 extending above its cooperating key-lever and is connected to an adjustable link 33. Each adjustable link 33 is connected at its inner end to a lug or projecting part 34 of one of the type-bars 35. Each type-bar is pivoted, at 36, to a segment 37 or to a hanger, as preferred, and at the forward part of said type-bar is a type head 38 having a plurality of type thereon. As each key-lever is depressed, the link 37 will operate its cooperating auxiliary lever 31 and through the link 33 will force the type of the type-bar with a pulling action upward and rearward for printing purposes.

An important feature of the invention are the links and their connection and action between the key-levers and the auxiliary levers. Each link 27 is of a skeleton character and has its inturned angular end 28 curved and adapted to rest in its normal position against the upper part of the bearing edge 39 of the

key-lever arm 25. The slot 26 is large enough for the end 28 to move from one side to the other and said end is held against disengagement by a part 40 forming a lip integral with the angular end 28 and which is adapted to be bent over so as to engage the outer face of the key-lever arm 25. The angular end 29 of the link 27 is somewhat shorter than the end 28 and may be straight with an integral part or end 41 similar to the lip or part 40 for the purpose of retaining the end 29 of the link in the slot 30 of the auxiliary lever. The slot 30, like the slot 26, is large enough for the end 39 to work from one side to the other and the inner bearing edge 42 of said slot 30 may be curved to form a bearing surface for the link end 29.

In the position shown, it will be noticed that the upper end 28 of the link has its bearing along the edge 39 at a point nearest the fulcrum rod 22, while the end 29 has its bearing point on the edge 42 of the slot 30 farthest from the pivot rod 31^a of the auxiliary levers. At this time and at the initial depression of a key-lever, the power arm of each key-lever 21 is greatest so that it is very easy initially to depress the key, but as the key is depressed, the bearings of the link shift by rolling or rocking action of the end 28 against the edge 39 and a rolling or rocking action of the end 29 against the bearing edge 42 of the slot 30 so that at the end of the depression, the bearing between the end 28 and the edge 39 is farthest from the pivot rod 22 and the bearing of the end 29 of the link along the edge 42 of the slot 30 of the auxiliary lever is nearest its pivot rod. The rolling or shifting action of the link 27 during the depression of the key, thus accelerates or increases the speed of the type toward the platen so that if the distance of a complete depression of any one key is divided into four parts, the position of the type during its travel from its normal position to its printing point would be substantially that indicated by the dots 43, 44, 45 and 46. That is, for the first quarter of its depression, the type would move approximately to the dot 43, the second quarter to approximately the dot 44, the third quarter to substantially the dot 45, and the last quarter to make the impression on the work sheet. It will thus be evident that by simply the automatic shifting or relative changing of the position of the link 27 and the key-levers and the auxiliary levers forms an effective means for changing the speed of movement of the upper end of the auxiliary lever 32. It will be also evident that the deep initial depression of the key necessary to raise the type just a fraction of the distance of its travel serves to give an easy velvety start to each key-lever and does away with the tiring effect of a very slightly accel-

erated key action. It will be further evident that by reason of the link 33 having a pulling action and arranged in substantially a horizontal plane, a direct pull is exerted on each type-bar. The links 27 constitute movement accelerating devices which are interposed between the key levers and the auxiliary levers and are wholly supported by the movable parts of the key action.

10 The auxiliary levers may each be restored by a spring 47 to its normal position, one end of each spring being secured to the lower end of the auxiliary lever and at the other end may be secured to a transversely extending rod 48 or otherwise. The auxiliary levers may be separated from each other and guided by means of a substantially U-shaped slotted comb plate 49, and the key-levers at the pivot point thereof may be also separated and guided by means of a substantially U-shaped slotted guide and comb plate 50. The auxiliary levers may vary in length, as shown in Fig. 2, and may also have their upper ends bent at various angles so as to give as direct a pull as possible to the type-bars. In such case if a uniform touch is to be maintained the floating link arrangement is changed accordingly to compensate for the otherwise uneven touch or action of the type-bars.

In Figs. 3 and 4, the link 51 is substantially the same as the link 27 except that the inturned end 29 is provided with an integral lug or lip 52 for retaining the link in operative engagement with its coöperating auxiliary lever 31. The lip or end 53 on the link end 28 in assembling is normally in alinement with the vertical edge of the integral inturned end 28 so that in assembling the end 29 is first passed through the slot 30 of the auxiliary lever 31 to cause the lip 52 to overlap the outer surface of the auxiliary lever and when thus engaged, the bendable lip or part 53 is bent over as shown, thus holding the link in proper engagement with both the key-lever and the auxiliary lever. The link ends 28 and 29 are shown as being straight instead of being curved but it will be understood that either one or both may be curved or straight and the slots in the key-levers and auxiliary levers also curved or straight as desired. It will be also understood that by changing the curvature of the bearing edges of either the links or key-levers and auxiliary levers, the extent and degree of acceleration may be changed at will. It will be further understood that to take care of the reduced movement of the two lower banks of keys, the lengths of the slots may be changed and the angle portions of the floating links widened to even up the touch and the depression of the different keys.

In Fig. 5, the type-bar 54 is connected by a link 55 to an arm 56 of a bell-crank lever

57. This bell-crank lever is pivoted on a rod or shaft 58 and takes the place of the auxiliary lever 31 of the form shown in Fig. 1. The arm 59 of the bell-crank lever 57 is slotted, at 60, and extending into the slot 61 of a link 62. The link 62 has an inturned end 63 which enters a slot 64 in a key-lever or key-operated lever 65. The slot 64 has a curved bearing edge 66 and the slot 60 has a curved bearing edge 67 for the link, said link having retaining lips 68 and 69 to hold the same in engagement with the auxiliary lever 57 and the key-lever 65. The key-levers 65 have keys 70 at one end and are pivotally held on a rod 71. The inner end 72 of the key-lever is adapted to engage the universal bar 73 to operate the escapement and ribbon mechanisms. The arms 72 of the different banks of key-levers may vary in length and still provide a uniform touch as already explained in the description of the construction shown in Fig. 1, and the action of the link 62 in shifting its bearing connection with the key-lever and auxiliary lever for the purpose of giving an accelerated movement to the type-bar, is substantially the same as that described in connection with said figure.

In Fig. 6, the construction is somewhat similar to that shown in Fig. 5. Here the type-bar 74 is connected by an adjustable link 75 to an auxiliary bell-crank lever 76. The bell-crank lever is pivoted on a transversely extending rod 77 and has its arm 78 adapted to engage the universal bar 79. The arm 80 of the auxiliary bell-crank lever 76 is provided with a slot 81 having a curved bearing edge 82 extending in a vertical direction. A link 83 has an inturned end 84 provided with a retaining lip 85 for holding said link movable in the slot 81 and the other end 86 of said link enters a slot 87 in an arm 88 of a bell-crank key-lever 89. The slot 87 has a curved bearing edge 90 forming a bearing surface for the inturned end 86 of the link and the said end 86 has a bendable end or lip 91 for holding the end in said slot. The key-lever 89 is pivoted on a transversely extending rod 92 and the arm 93 thereof is provided with a key 94 by which the said key-lever may be depressed. As in the other forms described, when the key 94 is depressed, the floating link 83 has its bearing or engaging portion of its inturned ends shiftable along the curved bearing surfaces of the key-lever and of the auxiliary lever in order that the movement of the type-bar may be accelerated as described in connection with the construction shown in Fig. 1.

From the foregoing, it will be evident that a simple and efficient key action is provided wherein the key-levers have a substantially uniform touch and are so arranged that a

direct pull is imparted to the type-bar and in such a way that an accelerated movement very slow at first but very rapid at the final part of the depression of the key is obtained; that the construction is such that substantially all of said parts may be stamped from sheet steel or other material and are so made that they may be readily assembled; that the construction and the connection between the key-lever and the auxiliary lever is such that a minimum amount of friction is obtained; and that said key action is compact and comparatively few parts are employed in its construction.

15 Having thus described my invention, I claim as new and desire to secure by Letters Patent:—

1. In a typewriting machine, the combination of a support, a platen, upwardly and rearwardly movable type-bars, a plurality of key-levers forming different banks, a rod forming a pivot for all of said levers, an auxiliary lever for each key-lever and type-bar, a connection between each auxiliary lever and a type-bar, and a shiftable double rocking connection between each key-lever and its coöperating auxiliary lever supported by said key lever and auxiliary lever and imparting an accelerated movement to said type-bar.

2. In a typewriting machine, the combination of a support, a platen, an upwardly and rearwardly movable type-bar, a key-operated lever, an auxiliary lever, a connection between said auxiliary lever and the type-bar, and a rocking and direct connection between said levers bodily shiftable relatively thereto for imparting an accelerated movement to said type-bar.

40 3. In a typewriting machine, the combination of a platen, an upwardly and rearwardly movable type-bar, a key-operated lever, an auxiliary lever, a connection between said auxiliary lever and said type-bar, and a rocking connection between said levers shiftable bodily relatively thereto and supported solely thereby for imparting an accelerated movement to the type-bar.

4. In a typewriting machine, the combination of a platen, type-bars, a plurality of key-levers forming different banks, a pivoted auxiliary lever for each key-lever, a connection between said auxiliary lever and a type-bar, and a shiftable floating and rocking link between each key-lever and its co-operating auxiliary lever.

5. In a typewriting machine, the combination of a platen, upwardly and rearwardly movable type-bars, a plurality of key-levers forming different banks, a rod forming a pivot for all of said levers, a pivoted auxiliary lever for each key-lever, a connection between said auxiliary lever and a type-bar, and a shiftable and floating rocking connection between each key-lever

and its coöperating auxiliary lever for imparting an accelerated movement to said type-bar.

6. In a typewriting machine, the combination of a support, a platen, upwardly and rearwardly movable type-bars, a plurality of key-levers forming different banks, a rod forming a pivot for all of said levers, an auxiliary lever for each key-lever, a connection between said auxiliary lever and a type-bar, and a double rocking link connection between each key-lever and its co-operating auxiliary lever.

7. In a typewriting machine, the combination of a type-bar having an upward and rearward movement, a key-operated lever, an auxiliary lever, a connection between the auxiliary lever and the type-bar, and a double acting shiftable link connection between the auxiliary lever and the key-operated lever.

8. In a typewriting machine, the combination of a type-bar, a key-operated lever, an auxiliary lever, a connection between the auxiliary lever and the type-bar, and a double rocking link forming a connection between the auxiliary lever and the key-operated lever.

9. In a typewriting machine, the combination of a type-bar having an upward and rearward movement, a key-operated lever, an auxiliary lever, a link connecting the auxiliary lever to the type-bar, and a link forming a double rocking shiftable connection between the auxiliary lever and the key-operated lever.

10. In a typewriting machine, the combination of a type-bar having an upward and rearward movement, a key-operated lever, a pivoted auxiliary lever, a link connection between the auxiliary lever and the type-bar, and a double rocking bodily movable connection between the auxiliary lever and the key-operated lever having a shiftable bearing and imparting an accelerated movement to the type-bar.

11. In a typewriting machine, the combination of a type-bar, a key-lever, and a floating connection interposed between the key-lever and the type-bar shiftably engaging the key-lever and partly supported by said lever.

12. In a typewriting machine, the combination of a type-bar, a key-lever, a pivoted auxiliary lever connected to the type-bar, and a bodily movable connection between the key-lever and the auxiliary lever shiftable at both ends with relation to the said key-lever and auxiliary lever for imparting an accelerated movement to said type-bar.

13. In a typewriting machine, the combination of a type-bar, a key-lever, and a floating shiftable double rocking connection between the key-lever and the type-bar.

14. In a typewriting machine, the combi-

5 nation of an upwardly and rearwardly striking type-bar normally held in a horizontal position, an auxiliary lever, a link normally positioned in substantially parallel relation to the type-bar and connecting said type-bar to one arm of said auxiliary lever, a key-lever, and a floating connection between the key-lever and the auxiliary lever and shiftable at both ends for imparting an accelerated movement to said auxiliary lever and said type-bar.

10 15. In a typewriting machine, the combination of a type-bar normally held in a horizontal position, a pivoted auxiliary lever, a link connecting said type-bar to one arm of said auxiliary lever, a key-lever, and a double acting connection between the key-lever and the auxiliary lever wholly supported by said levers for imparting an accelerated movement to said auxiliary lever and the type-bar.

15 20. 16. In a typewriting machine, the combination of an upwardly and rearwardly striking type-bar normally held in a horizontal position, a pivotally held auxiliary lever, a link normally positioned in substantially parallel relation to the type-bar and connecting said type-bar to one arm of said auxiliary lever, a key-lever having its pivot at the rear of said auxiliary lever, and a double acting floating link connection between the key-lever and the auxiliary lever for imparting an accelerated movement to said auxiliary lever and the type-bar.

25 30. 35. 40. 17. In a typewriting machine, the combination of a type-bar, an auxiliary lever, a connection between said lever and said type-bar, a key-operated lever, and a double rocking connection having a variable bearing with said key-operated lever and said auxiliary lever.

45 50. 55. 18. In a typewriting machine, the combination of a type-bar, a pivoted auxiliary lever, a connection between said lever and said type-bar, a key-lever, and a rocking link connection having a shiftable rocking bearing at both ends between said key-lever and said auxiliary lever and wholly supported thereby.

60 65. 19. In a typewriting machine, the combination of a type-bar, an auxiliary lever, a connection between said lever and said type-bar, a key-operated lever, and a rocking link having a variable bearing at both ends between said key-lever and said auxiliary lever.

70 75. 80. 20. In a typewriting machine, the combination of a type-bar, an auxiliary lever connected to said type-bar, a key-lever, and a floating connection between said key-lever and said auxiliary lever and rocking on each of said levers.

85 21. In a typewriting machine, the combination of a type-bar, an auxiliary lever, a link connecting said type-bar with said le-

ver, a key-operated lever having an integral portion provided with a slot, said auxiliary lever also being provided with a slot, a link having inturned ends of relatively different lengths engaging said slots and having a variable and shiftable bearing connection with said key-lever and auxiliary lever, and a spring for returning the auxiliary lever and key-lever to their normal position.

75 22. In a typewriting machine, the combination of a type-bar, an auxiliary lever, a link connecting said type-bar with said lever, a key-operated lever having a part thereof provided with a slot, said auxiliary lever also being provided with a slot, and a link having inturned ends of relatively different lengths engaging said slots and having a variable and shiftable bearing connection with said key-lever and auxiliary lever.

80 85. 23. In a typewriting machine, the combination of a type-bar, an auxiliary lever connected to said type-bar, a key-operated lever having an integral portion provided with an elongated slot, said auxiliary lever also being provided with an elongated slot, and a link having inturned ends of relatively different lengths engaging said slots and having a variable and shiftable bearing connection with said key-lever and auxiliary lever and wholly supported thereby.

90 95. 100. 24. In a typewriting machine, the combination of a type-bar, an auxiliary lever, a link connecting said type-bar with said lever, a key-operated lever provided with a slot, said auxiliary lever also being provided with a slot, and a floating link having ends of different lengths engaging said slots and having a variable shiftable bearing connection with said key-lever and auxiliary lever.

105 110. 115. 25. In a typewriting machine, the combination of type-bars, a link connected to one of the type-bars, a vertically arranged auxiliary lever for each type-bar having one arm connected to the link and having its other arm provided with a vertically arranged slot, a pivotally held key-lever for each auxiliary lever having an integral vertically extending part provided with a slot of greater length than the slot in the auxiliary lever, comb plates forming a guide and spacing means for the auxiliary levers and the key-levers, links having integral lips and having parts entering the slots of the key-levers and the auxiliary levers and having a changeable bearing connection therewith, and springs for returning the parts to their normal position.

120 125. 130. 26. In a typewriting machine, the combination of a type-bar, a link connected to the type-bar, a vertically arranged auxiliary lever having one arm connected to the link and having its other arm provided with a vertically arranged slot, a pivotally held key-lever having an integral vertically extending part provided with a slot of greater

length than the slot in the auxiliary lever, and a link having parts entering the slots of the key-lever and the auxiliary lever and having a changeable bearing connection therewith.

27. In a typewriting machine, the combination of a type-bar, a link connected to the type-bar, a vertically arranged auxiliary lever having one arm connected to the link and having its other arm provided with a vertically arranged slot with one edge curved, a pivotally held key-lever having an integral vertically extending part provided with a slot of greater length than the slot in the auxiliary lever, and a link having integral parts entering the slots of the key-lever and the auxiliary lever and having a changeable bearing connection therewith, said link having one of its bearing parts curved.

28. In a typewriting machine, the combination of a type-bar, a vertically arranged auxiliary lever having one arm connected to the type-bar and having its other arm provided with a vertically arranged elongated slot, a pivotally held key-lever provided with an elongated slot of greater length than the slot in the auxiliary lever, and a floating link having parts entering the slots of the key-lever and the auxiliary lever and having a changeable bearing connection therewith.

29. In a typewriting machine the combination of a type-bar, a key lever, and a variable movement device interposed between the type-bar and the key lever and wholly supported by the movable parts, said device having a shiftable fulcrum on the key-lever to give the type-bar a variable movement.

30. In a typewriting machine the combination of a type-bar, a key lever, a pivoted auxiliary lever connected to the type-bar, and a movement accelerating device interposed between the key lever and the auxiliary lever and wholly supported by said levers, said device being adapted to shiftably engage both of said levers to accelerate the movement of the type-bar to the printing point.

31. In a typewriting machine the combination of a type-bar, a key lever, and a movement accelerating device interposed be-

tween the key lever and the type-bar and wholly supported by the movable parts, said device having a shiftable connection with the key-lever to accelerate the movement of the type-bar to the printing point.

32. In a typewriting machine the combination of a type-bar, a key lever, a pivoted auxiliary lever connected to the type-bar, and a movement accelerating device interposed between the key lever and the auxiliary lever and wholly supported by said levers, the points of engagement between said device and the said levers moving from and toward the pivots of said levers during the movements of the key lever to accelerate the movement of the type-bar to the printing point.

33. In a typewriting machine, the combination of an upwardly and rearwardly striking type-bar normally held in a substantially horizontal position, a key-lever, an auxiliary lever, a link normally positioned in substantially parallel relation to the type-bar and connecting said type-bar to one arm of said auxiliary lever, and a floating link connecting the key-lever and auxiliary lever and having a rocking bearing on each lever for imparting an accelerated movement to said auxiliary lever and type-bar.

34. In a typewriting machine, the combination of an upwardly and rearwardly striking type-bar normally held in a substantially horizontal position, an auxiliary lever pivotally supported intermediate its ends, a link normally positioned in substantially parallel relation to the type-bar and connecting the type-bar to one arm of the auxiliary lever, a key-lever having its pivot at the rear of the auxiliary lever, and a floating link connecting said levers and supported solely thereby, said link having a shiftable rocking bearing on each lever for imparting an accelerated movement to the auxiliary lever and the type-bar.

This specification signed and witnessed this 14th day of August, A. D. 1914.

OTTO PETERMANN.
